UNITED STATES PATENT OFFICE.

ALEXANDER FORIN, OF NELSON, CANADA.

SASH-FASTENER.

SPECIFICATION forming part of Letters Patent No. 639,164, dated December 12, 1899.

Application filed March 20, 1899. Serial No. 709,868. (No model.)

To all whom it may concern:

Be it known that I, ALEXANDER FORIN, of Nelson, British Columbia, Canada, have invented a new and useful Improvement in Sash-Fasteners, of which the following is a specification.

My invention relates to sash fasteners and holders; and it has for its object a device of this class that will operate to fasten the sashes in closed position and also hold them at different elevations in a simple and efficient manner.

The invention consists in certain details of construction and arrangement of the parts, which I shall first describe and then particularly point out in the accompanying claim.

Reference is to be had to the accompanying drawings, in which—

Figure 1 is a face view of the holder for the lower sash shown detached. Fig. 2 is a detail side view of the lower pawl. Fig. 3 is an edge view thereof. Fig. 4 is a transverse vertical section of the lower holder detached. Fig. 5 is a horizontal section on the line 1 2, Fig. 1. Fig. 6 is a face view of the upper sash-holder. Fig. 7 is a side view thereof. Fig. 8 is a sectional side elevation of the same in locking engagement with a notched strip. Fig. 9 is a face view of said strip, and Fig. 10 is a face view of a window-sash with my improved sash-holder shown in locking engagement with the mid-rail lower sash.

Recesses are made in the window-jamb J and between the guiding-strips for the sashes to receive the casings C and C', in which are located the fastening and holding devices, the lower casing C being arranged for the fastening devices of the lower sash and the upper casing C' being adapted for the fastening devices of the upper sash, as will be hereinafter more fully explained. These casings are formed with journal-bearings d and d', in which are journaled spindles a and a', respectively, and wedge-shaped pawls A and A' are secured fixedly to or formed integral with such spindles.

Notched strips F and F' are secured to the stiles of the sashes adjacent the casings C and C', the pawls being brought into engage-

ment with the notches f and f' thereof to hold 50 the sashes at different elevations.

In order to normally hold the pawls in engagement with the notches, I provide leaf-springs e and e', which normally bear against the rear sides of the pawls when the latter 55 are in upright position, and in order to release the pawls at any time to move the sashes toward their closed positions I form non-circular openings b and b' in the spindles a and a', respectively, such openings being arranged 60 to receive the correspondingly-shaped ends of handle-rods B and B'. These latter are extended into the room through the jamb and have knobs E and E' on their inner ends and escutcheons D and D', in which they turn. 65 One of the principal objects of my invention is to so mount the lower pawl that it will hold the lower sash securely locked when in closed position, and to this end I locate the casing C at such a point in the jamb that when the 70 pawl A is reversed or turned down, as shown in Fig. 10, its point will rest upon the upper or mid-rail of the lower sash, thereby preventing the lower sash from being raised until the pawl is turned and freed from said rail. It 75 will be seen, therefore, that the lower pawl A is not only useful in holding the lower sash raised at different elevations, but is capable of performing the additional function of locking the lower sash closed.

Having thus described my invention, what I claim as new, and desire to secure by Letters Patent, is—

A sash holder and fastener, comprising a bearing in the window-jamb at a point above 85 the lower sash when it is closed, a pawl rotatably mounted in the bearing and normally engaging said lower sash when the latter is raised, the said pawl being of such length that when turned down or reversed into vertical 90 position its free point will abut against the mid-rail of the lower sash whereby to fasten such sash in closed position, as set forth.

ALEXANDER FORIN.
